Patented Apr. 1, 1913.

Application filed December 7, 1912. Serial No. 735,537. Term of patent 14 years.

To all whom it may concern:

Be it known that I, WALTER L. SIEWERS, a citizen of the United States, residing at Winston-Salem, in the county of Forsyth and State of North Carolina, have invented a new, original, and ornamental Design for an Undergarment, of which the following is a specification, reference being had to the accompanying drawing, forming a part thereof.

The drawing is a perspective view of the garment seen from the front.

The garment shown in the accompanying drawing is composed of a tubular knit fabric 1 having the wales of the knitting running longitudinally of the garment cut from opposite sides as at 2 and with a central front cut 3 and central back cut 4, such cuts 3 and 4 being long narrow V-shaped cuts, the front cut being longer than the back cut and the cuts 2 extending a considerable distance into the body 1 of the garment. The fabric of the garment is extended as at 5 in tapered lines upwardly from the body forming shoulder straps with ornamental binding or beading 6 finishing the cuts 2 and ornamental binding 7 finishing the cuts 3 and 4, such binding 7 extending entirely around the two cuts 3 and 4 while two pieces of the binding are employed as at 6 to finish the cuts 2, such binding extending along beside the straps 5 to complete the shoulder straps with ornamental edging.

I claim—

The ornamental design for an undergarment as shown and described.
